(57) **CLAIM**

The ornamental design for a physiotherapy support device, as shown and described.

DESCRIPTION

FIG. 1 is a rear and left side perspective view of a first embodiment of a physiotherapy support device showing my new design.

FIG. 2 is a rear view of the physiotherapy support device of FIG. 1.

FIG. 3 is a front view of the physiotherapy support device of FIG. 1.

FIG. 4 is a top view of the physiotherapy support device of FIG. 1.

FIG. 5 is a bottom view of the physiotherapy support device of FIG. 1.

FIG. 6 is a left side view of the physiotherapy support device of FIG. 1.

FIG. 7 is a right side view of the physiotherapy support device of FIG. 1.

FIG. 8 is a front and right side perspective view of a second embodiment of a physiotherapy support device showing my new design.

FIG. 9 is a rear view of the physiotherapy support device of FIG. 8.

FIG. 10 is a front view of the physiotherapy support device of FIG. 8.

FIG. 11 is a left side view of the physiotherapy support device of FIG. 8.

FIG. 12 is a right side view of the physiotherapy support device of FIG. 8.

FIG. 13 is a top view of the physiotherapy support device of FIG. 8; and,

FIG. 14 is a bottom view of the physiotherapy support device of FIG. 8.

The broken lines in the drawings depict portions of the physiotherapy support device that form no part of the claimed design.

1 Claim, 8 Drawing Sheets
